UNITED STATES PATENT OFFICE.

ROCKWELL M. MACCORMAC, OF KANSAS CITY, MISSOURI.

GARMENT SUPPORTER.

Application filed March 10, 1924. Serial No. 698,102.

This invention relates to improvements in garment supporters, particularly of the class adapted to support hosiery or stockings.

One of its objects is to provide a supporter or garter having the fewest possible number of parts and of extreme simplicity in form, and so arranged that it can be affixed and adjusted readily without effort and uncertainty, and the whole so designed as to offer a garter that is reversible and useable in a right or left position on either leg with equal facility, efficiency and comfort, and avoiding all necessity for and the expense and trouble of making and using rights and lefts.

Another object is to provide a garter having metal parts so arranged and protected that they cannot come into contact with the leg, and of substantial construction to last indefinitely, and so designed that when certain fabric parts become worn out in use they may be readily removed and replaced with new fabric and the device be thus made fit for further service.

A further object is to provide a practical article of good appearance and of such simple form that it can be made and sold in large quantities at small cost.

With the objects named in view, the invention consists in certain novel and useful features of construction and organization of parts as hereinafter described and claimed; and in order that it may be fully understood, reference is to be had to the accompanying drawing, in which:

Figure 1 is a perspective view of a garter embodying the invention.

Figure 2 is a section on the line II—II of Figure 1.

Figure 3 is a section on the line III—III of Figure 1.

Figure 4 is a perspective view of certain parts of the invention.

In the said drawing, where like reference characters identify corresponding parts in all of the figures, 1 represents a base or pad preferably of fabric material in any suitable form, and having attached as at 2 a looped strip of tape 3 or other material having a knob 4 secured to its outer face near its free end.

A clasp in the form of a metal ring 5 is provided, one side of which is flat or straight to form a bridge portion 6. Pivottally secured to the bridge is an elongated metal loop 7 having somewhat widely spaced ends

8 hooked at their extremities around the bridge 6, and between said ends 8, the bridge is secured to the pad by means of a loop 9 formed in the tape 3 by sewing it at points 10 and 11 above and below said bridge (see Figure 2).

An elastic webbing 12 is provided, one end of which is irremovably but slidably secured to a free section of the circular part 65 of the ring 5, preferably by means of a closed hook or hinge 13 formed with a slot 14 to retain the webbing in position. The other end of the webbing 12 is secured in a slot 15 formed at one end of an open or detachable hook 16 adapted for self-adjustable or slidable engagement with the ring 5.

It is pointed out that all points of attachment and engagement of the base or pad and the clasp metal parts 5 and 7 and the webbing fastenings 14 and 16 are accomplished on the outer or face of the tape 3 and the pad 1, which thus prevents the metal parts from coming into direct contact with the leg, the pad presenting a flexible cushion 80 which readily conforms to the curvature of the leg.

It is also apparent from the manner in which the loop 7 is secured to the bridge 6, and the ring 5 secured to the pad 1 by means of the bridge 6 and the tape 3, that the free ends of the loop and ring can be readily raised or swung toward a perpendicular position as regards the pad 1, and returned to normal position without interfering one 90 with the other.

To operate the garter, the loop 7 is easily manipulated so that the top of the hose may be placed over the knob 4, and both passed between the arms of the loop 7 and moved downward into a narrower or constricted portion 17 of the loop, which will clamp the hose in position. The end of the elastic webbing having the hinge 13 may be freely slipped on the ring 5 from one side to the other, always leaving one side of the ring free. The other end of the webbing having the hook 16 may be passed to the right or left to encircle the leg and may be readily hooked onto the opposite or free side of the ring, which may be raised away from the pad 1 to facilitate such engagement. There can thus be no uncertainty as to the hook 16 having been properly and securely fastened in the right place, and the said hook may be as readily detached. As the webbing is shiftable at both ends, it can readily ad-

just itself at any point on the ring for a balanced pull from all angles.

It will be evident from the above description that by means of a comparatively few parts of simple form, the garter is self-adjustable, reversible and equally serviceable for either leg, and avoids all necessity for rights and lefts. When the elastic webbing becomes worn in use it may be removed from the hinge 13 and the hook 16 and be readily replaced with new webbing, and the renewed supporter used indefinitely as before.

From the above description, it will be apparent that I have produced a device of the character described which possesses all of the features of advantage set forth as desirable, and while I have described and claimed the preferred embodiment of the same, I reserve the right to make all changes properly falling within the spirit and scope of the appended claims.

I claim:—

1. In a hose supporter, in combination, a pad having a pendent loop of tape provided with a knob near its lower end, a circular ring over the pad, having a straight side forming a bridge, and a metal loop through which the knob may pass and a constricted portion adapted to engage said knob and having its upper extremities encircling the bridge; said bridge being secured to the pad by the tape, between the arms of the loop.
2. In a hose supporter, in combination, a pad having a pendent loop of tape provided

with a knob near its lower end, a circular ring having a straight side forming a bridge portion which is secured to the pad by said tape, a metal loop adapted to engage the knob and having its upper extremities bent around the bridge, an elastic webbing slidably attached at one end to the ring, and a hook secured to the other or free end of the webbing; the said ring and the said loop being free for independent hinge movements, and the slidable end of said webbing being shiftable to either side of the ring and the other end being capable of detachable hooked engagement with the opposite side of the ring.

3. In a hose supporter, the combination of a ring having a lower chordal portion, a leg band having a member at one end to secure the band to the ring pivotally and slidably and having means for detachably securing the other end to either side of the ring, a loop with its ends pivotally encircling the chordal portion of the ring and having an attenuated or constricted lower end and an expanded intermediate portion, a knob member to engage the restricted portion of the loop, and a fabric member to which the chordal portion of the ring and the knob member are secured, the loop, and the ring at its chordal portion, respectively having coincidental hinge action outwardly and upwardly and outwardly and downwardly with respect to said fabric member.

In witness whereof I hereunto affix my signature.

ROCKWELL M. MACCORMAC.
